UNITED STATES PATENT OFFICE.

HENRY A. HOESCHEN, OF OMAHA, NEBRASKA, ASSIGNOR TO HOESCHEN MANUFACTURING COMPANY, OF OMAHA, NEBRASKA, A CORPORATION OF NEBRASKA.

RAILWAY SIGNALING MECHANISM.

1,111,257.

Specification of Letters Patent.

Patented Sept. 22, 1914.

Original application filed April 3, 1906, Serial No. 309,706. Divided and this application filed September 3, 1912. Serial No. 718,320.

To all whom it may concern:

Be it known that I, HENRY A. HOESCHEN, a citizen of the United States, and a resident of Omaha, in the county of Douglas and State of Nebraska, have invented certain new and useful Improvements in Railway Signaling Mechanism, of which the following is a specification.

My invention relates to railway signaling mechanism, and especially to devices for indicating at a station or stations the operation of signal-actuating mechanism of the class shown in my copending application, filed April 3, 1906, Serial No. 309,706, and of which the present application is a division.

It is the object of my invention to provide simple, durable and inexpensively maintained mechanism by which a plurality of signal-actuating instruments, located at different positions and operating independently of each other, may be connected in a single line-circuit with a station or stations, and the operation of each of the several instruments indicated at the stations.

A further object of my invention is to provide means for reducing the resistance in the line-circuit, and for protecting the generators from injury by lightning or other foreign currents in the line-circuit.

A further object of my invention is to provide means by which, of the electrical impulses produced by a magneto generator at any point in the line-circuit, unidirectional impulses only will be caused in the line-circuit, so that polarized indicating instruments may be employed at the stations.

In the accompanying drawings Figure 1 is a diagrammatic view of a mechanism embodying my invention, Fig. 2 is a view of one of the generators at the beginning of the actuation thereof, Fig. 3 is a similar view at a further stage in the operation thereof, and Fig. 4 is a similar view showing the same near the conclusion of the operation.

In the construction of my mechanism I employ a simple form of magneto-electric generator, comprising U-shaped permanent magnets 1, coil-cores 2 extending from the poles of the magnets, coils 3 disposed around the said cores, and an armature 4 pivoted at one end and arranged so as to be normally in

engagement with the ends of the coil-cores. The coil-cores and the armature are, of course, made of paramagnetic material such as soft iron, so that there is a complete magnetic circuit when the armature is in normal position.

The signal-actuating mechanism described in my application before referred to, and in connection with which the indicating mechanism herein considered is employed, has a shaft 5 which revolves during the operation of the mechanism. On said shaft is a toothed wheel 6, and the magneto-electric generator is positioned so that the teeth on said wheel 6 may engage the armature 4 to periodically pull the same away from the pole-pieces or coil-cores which it normally engages.

Near the end of the armature 4 adjacent to the wheel 6 is a contact spring 7 which engages a contact 8 when the armature is in normal position. The coils 3 are connected in a line-circuit formed through the wires 9 and 10. The wire 9 is also connected with the contact 8 and the wire 10 is connected with the armature 4 so that when the spring 7 and contact 8 are in engagement the coils 3 are shunted through the armature. The toothed wheel 6 is turned in the direction, relative to the armature, indicated by the arrows in the several figures. As each tooth of the wheel approaches the armature it first engages the spring 7 and moves it out of engagement with the contact 8, thus breaking or opening the shunt-circuit, as shown in Fig. 2. As the movement of the wheel continues the armature is pushed away from the magnet-pole, as shown in Fig. 3, thus making a gap in the magnetic circuit and causing a rapid decrease in the magnetic flux through the coils, so that an electrical impulse is generated therein, and said impulse will pass over the line-circuit formed through the wires 9 and 10. As the movement of the wheel continues it releases the contact-spring 7 which returns to engagement with the contact 8, as shown in Fig. 4, and thus closes the shunt-circuit.

Then, when the armature is released and returns to engagement with the poles, the electrical impulse generated in the coils by the increase of the magnetic flux will pass almost exclusively through the low-resistance shunt-

circuit instead of going to the line-circuit. The teeth of the wheel 6 may be spaced so as to give any desired sequence to the electrical impulses caused in the line-circuit, so that said impulses when received at a station may constitute a distinctive signal and serve to indicate at such station the operation of the particular device that produced them.

In Fig. 1 I have shown several of the instruments, as at A, B and C, connected in series with each other and the stations M and N. In practice the instruments might be located at any desired distance from each other and from the stations, and each instrument might be operated by signal-actuating mechanism of the kind before mentioned. Any suitable number of the instruments may be connected in the same line-circuit and the toothed wheels 6 provided with differently spaced teeth so that the operation of each instrument will cause a signal different from the others.

It will be obvious that the impulses produced by each instrument of the series will pass almost wholly through the shunt-circuits of the other instruments instead of through the coils thereof, the shunt-circuits thus enabling a number of the instruments to be placed in series in the same line-circuit without causing undue resistance therein. The shunt-circuits also serve to prevent the generator-coils being burned out or otherwise injured by lightning, or by electrical currents from other wires which might become crossed with the wires of the line-circuit.

As a result of the opening and closing of the shunt-circuits in the manner described, the operation of each instrument causes in the line-circuit current-impulses that are of appreciable strength in one direction only. For while the impulses produced in the generator-coils by the movements of the armature away from and toward the poles are alternate in direction, the impulses caused by the latter movements pass, in appreciable amount, through the shunt-circuit only. Thus, by employing polarized receiving instruments at the stations, the operation of two instruments in the same line-circuit might be differentiated by arranging them so as to produce impulses of opposite polarity in said line-circuit.

Now, having described my invention, what

I claim and desire to secure by Letters Patent is:

1. In a device of the class described, an actuating-shaft, a toothed wheel carried by the shaft, an armature engageable by the toothed wheel, means forming a magnetic circuit through the armature, coils wound upon a part of the magnetic circuit, a line-circuit connected with the coils, a shunt-circuit connected with the coils, and a contact carried by the armature and controlling the shunt-circuit.

2. The combination with actuating mechanism, of a toothed wheel driven by the actuating mechanism, a magneto-electric generator having coils and provided with an armature arranged for reciprocating movement, a line-circuit connected through the coils, a shunt-circuit connected in parallel with the coils, and means for opening said shunt-circuit during movement of the armature in one direction and for closing the shunt-circuit during movement of the armature in the other direction.

3. The combination with a series of actuating devices, of a magneto-electrical generator for each actuating device, said generators each having coils and an armature, a line-circuit connected through the coils of all the generators, a shunt-circuit for the coils of each generator, means driven by each actuating device for moving the armature of the respective generator, and means controlling the shunt-circuits and operated by the respective armature-moving means.

4. The combination with a magneto-electrical generator having coils, and an armature arranged for reciprocating movement, of means for actuating said armature, a main circuit through the coils, a shunt-circuit for the coils, and means controlling the shunt-circuit and controlled by the armature actuating means, whereby the shunt-circuit is closed during movement of the armature in one direction and is open during the movement of the armature in the opposite direction.

In testimony whereof I have hereunto subscribed my name in the presence of two witnesses.

HENRY A. HOESCHEN.
